Inventor:

Clarence Elliott Hedrick

UNITED STATES PATENT OFFICE.

CLARENCE ELLIOTT HEDRICK, OF NEWTON, KANSAS.

POULTRY FEEDER.

Application filed April 15, 1927. Serial No. 184,124.

My invention relates to poultry feeders, and especially to those wherein a guard is employed to prevent fowls from scattering the food, and it consists in the combinations, 5 constructions and arrangements herein described and claimed.

An object of my invention is to provide a feed trough embodying a guard which may be readily removed therefrom, to facilitate 10 cleaning of the trough.

A further object is to provide a guard which will readily accommodate itself within the interior of a feed hopper, and also prevent displacement thereof by the 15 fowls.

A further object is to provide a guard which will be readily interchangeable with hoppers of varied interior dimensions.

Other objects and advantages will appear 20 in the following specification, and the novel features of the invention will be particularly pointed out in the appended claims.

My invention is illustrated in the accompanying drawings, forming part of this application, in which 25

Figure 1 is a top plan view of my trough and guard,

Figure 2 is a side elevation thereof,

Figure 3 is an end elevation, and

30 Figure 4 is a cross section on the line 4-4 of Figure 2.

In carrying out my invention, I provide a rectangular trough 1, having straight side walls 2, bottom 3 and end walls 4. The bottom 3 and end walls 4 are cut so as to provide flanges 5 which are bent in such manner as to lie in the same plane as the end walls 4. The flanges may be secured to the end walls in any approved manner, 40 as by soldering.

To facilitate handling of the hopper, the end walls 4 are curved outwardly to form a rolled edge 6, providing hand-holds, as may be clearly seen in Figure 2.

45 The side walls 2 are curved inwardly to form a rolled edge 7, this edge being of such size as to extend well within the interior of the trough.

A guard, generally indicated by the numeral 8, is provided, this guard being of a length to be set within the trough 1, and extends from one end wall to the opposite end wall.

50 The guard 8 is formed by bending a single strand of wire to provide a series of coils 9, these coils being of approximately equal

diameter and of a size to frictionally engage the inner edge of the rolled edges 7 of the trough. In order that the coils 9 may be held in proper spaced relation with one another, a rod 10 is secured, by welding or 60 soldering, to the perimeter of alternate coils (see Figure 1), this rod extending longitudinally of the guard, as shown. Additional rods 11 are positioned slightly below the horizontal axis of the coils 9 of the 65 guard, and secured rigidly to each of the coils, by soldering or otherwise.

A foot or base 12 may be soldered to the rod 10, intermediate its length, thus giving a solid support to the guard upon the base 70 of the trough.

It should be noted that alternate coils of the guard are not attached to the rod 10, but are curved inwardly toward the axis of the coils, as at 13, forming a helix 14. 75 The wire from which the guard is constructed is of a resilient character, tending to spring outwardly into frictional contact with the edges 7 of the trough, and this tendency is still further added in those coils 80 wherein the helix 14 is involved.

It will be apparent that I have provided a guard construction which may be readily applied to troughs of various widths, and at the same time insuring absolute retention 85 of the guard within a trough, due to the resilient frictional contact of the coils of the guard with the edges of the trough.

It should be noted that by providing inwardly projecting edges on the side walls of the trough 1 at such height as to contact 90 with the coils of an interposed guard, at a point well above the horizontal axis of the coils, a substantial binding action is effected at the point of contact.

I claim: —

1. An improved guard for poultry feeders of the character described comprising a resilient wire coiled in a helix, a longitudinal support rod secured to the periphery of certain coils of said guard, certain other 100 coils being unattached, and means upon the interior of the unattached coils to permit expansion and contraction of said last named coils.

2. An improved guard for poultry feeders of the character described comprising a resilient wire coiled in a helix, a longitudinal support rod secured to the perimeter of certain coils of said guard, certain other 105 coils being unattached and bowed inwardly 110

whereby to permit diametrical enlargement and contraction of the last named coils.

3. In a poultry feeder, a trough having side walls extending upwardly and projected inwardly to provide a rolled edge, a resilient guard within said trough, said guard comprising a wire coiled in a helix and be-

ing in frictional contact with said rolled edge, and brace rods secured to said helices at a point below the horizontal axis of said helices, whereby said helices will be free to expand and contract at their upper portions. 10

CLARENCE ELLIOTT HEDRICK.
